AIR AND SIGNAL LINE CONNECTION FOR
RETRACTABLE COUPLERSHarry H. Wolfe, Columbus, Ohio, assignor to The
Buckeye Steel Castings Company, Columbus,
Ohio

Application April 3, 1944, Serial No. 529,308

10 Claims. (Cl. 213—1)

This invention relates to the air and signal lines used in railway trains and more particularly to hose connections employed with retractable couplers of the type disclosed in my application Serial Number 526,762, filed March 16, 1944.

When locomotives are double headed, it is desirable to have the air brake line and the air signal line coupled between the two locomotives. It is, also, desirable to use the standard length of air hose so that proper clearances are provided for the air hose when coupled. There are certain fixed locations for the air and signal lines with reference to the pulling face of the coupler so as to provide the proper clearances and operating conditions for the air and signal hose.

When the coupler is retracted, a much better appearance is provided if the air and signal hose are not fixed to the front end of the locomotive and can be retracted with the coupler.

In accordance with the invention disclosed in my above-mentioned application, the locomotive pilot is provided with a pocket in which a door is mounted for movement about a vertical axis, and the door has one face coinciding with the face of the pilot when the coupler is in retracted position, and another recessed face from which the coupler projects when in coupling position.

The primary object of the present invention is to provide air brake line and air signal line connections designed to be mounted on the recessed face of the door structure, and to move with the latter into a concealed position within the pilot when the coupler is retracted.

With the foregoing objects outlined and with other objects in view which will appear as the description proceeds, the invention consists in the novel features hereinafter described in detail, illustrated in the accompanying drawings, and more particularly pointed out in the appended claims.

In the drawings,

Fig. 1 is a fragmentary front elevation of a pilot and retractable coupler of the type disclosed in my earlier application and with my improvements applied thereto.

Fig. 2 is a side elevation partly in vertical section, the section being taken on the line 2—2 of Fig. 1.

Fig. 3 is a plan view of a clamp forming part of my improvements.

Referring to the drawings, 4 designates a pilot having an anticlimbing projection 5, below which there is a doorway 6 at the front of a pocket 7 in which a door structure 8 is mounted for movement about a vertical axis. The door structure 55

has oppositely disposed walls, only one of which 9 is shown, and these walls coincide with the inclined face 10 of the pocket for streamlining. The wall of the door structure which is illustrated 5 is provided with a recess 11 from which a coupler 12 projects, and it will be understood that if the door structure is turned about the vertical axis on which it is mounted, the coupler will be moved into the pocket 7 to retracted position.

10 In accordance with the present invention, an air line 13 extends through the upper portion of the pilot above the door structure and terminates in a shut-off angle cock 14 positioned at a convenient point above the coupler. A signal line 15, also, extends through the pilot and is provided with a shut-off valve 16 located adjacent to the air line. Angle cock 14 and valve 16 are fitted respectively with short lengths of hose 17, 18 to which are fastened couplings 19, 20, which terminate slightly above the doorway 6, as shown in Fig. 2, so as not to interfere with opening and closing the pilot door structure 8.

At an intermediate point on the front wall 9 of the door structure, and firmly secured thereto 25 at one side of the recess 11 is a bracket 21 (Fig. 3) designed to clamp pipe fittings 22 and 23 to the door structure, and an air hose 24 has a nipple 25 at one end thereof which screws into fittings 22, and is provided at its opposite end with 30 a conventional coupling 26 designed to engage coupling 19. Similarly, a hose 27 has a nipple 28 at one end to screw into the pipe fitting 23, and a coupling 29 at its upper end for engagement with the coupling 20.

35 Standard length air and signal hose 30, 31 have nipples 32, 33 at their upper ends for engagement respectively with the fittings 22, 23, and terminate in conventional couplings 34, 35 adapted to be coupled with air and signal lines respectively 40 of an adjacent car (not shown).

When the coupler 12 is in coupling position, hooks 36 and 37 connected to an eye 38 on the door 9, tends to keep the couplings 19—26 and 20—29 connected, and the couplings 34 and 35 45 are then ready to be coupled in the usual way.

When it is desired to retract the coupler by swinging the door structure 180° about its vertical axis, couplings 19—26 and 20—29 are uncoupled and hooks 36, 37 of hose 24, 27 are released from eye 38 and the hose laid over the top of the coupler shank as indicated in dotted lines in Fig. 1. Couplers 34 and 35 are fastened to dummy couplings 39, only one of which is shown (Fig. 1). They are fixed to the door structure and arranged in the recess 11 by means of a chain 40 con-

nected to an eye 41. All hose is now positioned out of the way so as not to interfere with retracting the coupler. Of course, the reverse operation will place the parts in proper position for coupling hose to an adjacent car in the usual manner.

From the foregoing, it is believed that the construction, operation and advantages of the invention may be readily understood, and I am aware that changes may be made in the details disclosed without departing from the spirit of the invention, as expressed in the claims.

What I claim and desire to secure by Letters Patent is:

1. The combination with a locomotive pilot provided with a pocket in which a door structure is movably mounted, and a coupler is carried by the door structure, of a pipe fitting secured to the door structure, hose extending in opposite directions from the pipe fitting and terminating in pipe couplers, a fluid-conducting line connected to the pilot and provided with a shut-off cock, and means operatively and detachably connecting one of said couplers to said cock.

2. The combination with a locomotive pilot provided with a pocket in which a door structure is movably mounted, and a coupler is carried by the door structure, of a pipe fitting secured to the door structure, hose extending in opposite directions from the pipe fitting and terminating in pipe couplers, a fluid-conducting line connected to the pilot and provided with a shut-off cock, and means operatively and detachably connecting one of said couplers to said cock, said means comprising a hose connected to the shut-off cock and a coupler connected to the last-mentioned coupler.

3. The combination with a locomotive pilot provided with a pocket in which a door structure is movably mounted, and a coupler is carried by the door structure, of a pipe fitting secured to the door structure, hose extending in opposite directions from the pipe fitting and terminating in pipe couplers, a fluid-conducting line connected to the pilot and provided with a shut-off cock, means operatively and detachably connecting one of said couplers to said cock, and flexible means detachably connecting one hose to the door structure.

4. The combination with a locomotive pilot provided with a pocket in which a recessed door structure is movably mounted and a coupler is carried by the recessed portion of the door structure, of a pipe fitting secured to the door structure adjacent to the recess thereof, hose extending in opposite directions from the pipe fitting and terminating in pipe couplers, a fluid-conducting line connected to the pilot and provided with a shut-off cock, and means operatively and detachably connecting one of said couplers to said cock.

5. The combination with a locomotive pilot provided with a pocket in which a door structure is movably mounted, and a coupler is carried by the door structure, of a pipe fitting secured to the door structure, hose extending in opposite directions from the pipe fitting and terminating in pipe couplers, a fluid-conducting line connected

to the pilot and provided with a shut-off cock arranged above the door structure, and means operatively and detachably connecting one of said couplers to said cock.

5 6. The combination with a locomotive pilot provided with a pocket in which a door structure is movably mounted, and a coupler is carried by the door structure, of a pipe fitting secured to the door structure, hose extending in opposite directions from the pipe fitting and terminating in pipe couplers, a fluid-conducting line connected to the pilot and provided with a shut-off cock, means operatively and detachably connecting one of said couplers to said cock, and means 10 for detachably securing the other one of said couplers to the door structure.

7. The combination with a locomotive pilot provided with a pocket in which a door structure is movably mounted and a coupler is carried by the door structure, of a plurality of pipe fittings secured to the door structure, hose extending in opposite directions from each pipe fitting and terminating in pipe couplers, fluid-conducting lines projecting from the pilot and provided with 20 shut-off valves, and means operatively and detachably connecting certain of said couplers to said valves.

8. The combination with a locomotive pilot provided with a pocket in which a door structure is 30 movably mounted and a coupler is carried by the door structure, of a plurality of pipe fittings secured to the door structure, hose extending in opposite directions from each pipe fitting and terminating in pipe couplers, fluid-conducting lines projecting from the pilot and provided with 35 shut-off valves, means operatively and detachably connecting certain of said couplers to said valves, and flexible means detachably connecting certain of the hose to the door structure.

9. The combination with a locomotive pilot provided with a pocket in which a door structure is movably mounted and a coupler is carried by the door structure, of a plurality of pipe fittings secured to the door structure, hose extending in 40 opposite directions from each pipe fitting and terminating in pipe couplers, fluid-conducting lines projecting from the pilot and provided with shut-off valves, means operatively and detachably connecting certain of said couplers to said valves, 45 and means detachably connecting the other of said couplers to the door structure.

10. The combination of the locomotive pilot provided with a pocket in which a door structure is movably mounted and a coupler is carried by the door structure for movement into coupling position in front of the pilot or to retracted position within the pocket, of pipe fittings secured to the door structure, hose extending in opposite directions from each pipe fitting and terminating in pipe couplers, fluid-conducting lines projecting from the pilot and provided with shut-off valves, means operatively and detachably connecting certain of said couplers to said valves, the last-mentioned couplers being adapted to move with the hose and coupler into the pocket, and means detachably securing certain of the couplers to the door structure.

HARRY H. WOLFE.
